UNITED STATES PATENT OFFICE.

ERNST HUBER, OF BROOKLYN, NEW YORK, ASSIGNOR OF ONE-HALF TO WILLIAM MEISTER, OF BROOKLYN, NEW YORK.

GAS-ENGINE.

1,135,021.

Specification of Letters Patent.

Patented Apr. 13, 1915.

Application filed March 5, 1913, Serial No. 751,983. Renewed August 19, 1914. Serial No. 857,608.

To all whom it may concern:

Be it known that I, ERNST HUBER, a citizen of the United States, residing in Brooklyn, in the county of Kings and State of New York, have invented certain new and useful Improvements in Gas-Engines, of which the following is a specification.

The object of my invention is to increase the efficiency and economy of and to enable 10 higher compression to be utilized in "Otto," or "four-cycle" internal combustion engines run with gas or volatile fuel; and to render their cycles reliably uniform and uninterrupted.

15 It is well known that the economy of heat engines is almost directly proportioned to the initial pressure utilized; and that, in "four-cycle" engines, as usually made, high compression is impossible because it would cause excessive temperatures in and pre- 20 ignition of the explosive mixture, and consequent interruptions in the cycle.

25 My invention consists in improvements in such engines and in their mode of operation which enables me to build engines of such general type in which compression can be much higher than has heretofore been possible, ignition is under control, the cylinder charge of explosive mixture cannot be fired 30 accidentally or out of sequence and the engine runs reliably, with a perfect cycle.

In the drawings, Figure 1 is an axial section of an engine embodying my improvements, and Figs. 2, 3, 4, 5, 6 and 7 are dia- 35 grammatic views showing successive stages in the engine-cycle.

40 My improved engine-cycle is based on a discovery made by Clement and Desormes during their determination of the specific heat of gases, to wit:—that when a highly compressed gas is permitted to flow, through a suitably regulated passage, into a chamber containing a gas at lower pressure, the compression of the latter causes sensible heat, 45 which raises its temperature and thereby the degree of its compression.

The engine illustrated (Fig. 1) comprises 50 a cylinder 1, with a water jacket 2, a piston 3, connected by a connecting rod 5 with a crank 4 on a main shaft 6, suitably mounted in bearings 7 on a standard 8, and provided with a fly wheel 9 which revolves with the arrow 10. A secondary shaft 11, is mounted on said standard parallel with and geared to 55 the main shaft by a one-to-two reducing

train comprising gears 19 and 18 on said main and secondary shafts respectively.

Fixed to the secondary shaft 11 are a cam 12 and a sprocket wheel 23. The cam-shaft 20, suitably mounted on the bed plate 21, has fixed to it a sprocket wheel 24 connected by a chain 25 with and driven by the sprocket 23 and secondary shaft 11; and 60 3 cams, 22 and 59 which control the fuel supply, and 70, which operates a valve 55, to 65 control the communication of the engine cylinder with an air reservoir B and primary explosion chamber A, as will be described.

The supply of air and the exhaust are 70 directly to and from the primary explosion chamber, through parts located in opposite limbs of its head 26 and controlled by the air-inlet valve 27 and exhaust valve, 28, which are respectively seated by springs 29 75 and 30, and connected with the secondary shaft 11 and its cam 12 by a lever train comprising a rocking lever 13, pivoted at 14, and provided with a pin 15 held in engagement with the face of the cam 12 by a spring 80 16 strained between said lever and a fixed abutment 17; a valve lever 32 medially pivoted on an extension 31 of the head 26, having its driving arm 35 connected by a link 36 and pin 37 with the rocking lever 13 and 85 provided with oppositely-located tappets 34 and 38 the former of which completes the opening and times the closing of the air inlet valve 27 while the latter operates the exhaust valve 28. 90

The above described organizations, while adapted to control the alimentation and exhaust of a stationary engine, such as illustrated, and to cause it to run according to my improved cycle, are withal, non-essential, 95 and in engines of other types may be replaced by organizations of like functions but adapted to the particular uses for which such engines are designed.

I will now describe those features which 100 are essential, and comprise the construction of the cylinder, and the modes of supplying fuel and firing. I provide a primary explosion chamber A, and an intermediate chamber or reservoir B, between it and the working cylinder C. Fresh air is admitted to the primary explosion chamber A through an inlet pipe 38 and passage 40 and the inlet port controlled by the inlet valve 27; which is located near one side of said 110

chamber; and the exhaust takes place near the opposite side through the exhaust port controlled by the exhaust valve 28, a passage 41 and an exhaust pipe 39. The primary 5 explosion chamber A and reservoir B communicate through a passage 66 formed in the separating partition 65, protected by a flame proof 67, to prevent pre-ignition, and located nearly in line with the inlet port, about which a deflector 64 is arranged to 10 deflect incoming air toward said passage. The reservoir B communicates with the working cylinder C by a U-shaped passage 42 which is controlled by a valve 55 connected with and operated by the cam 70 on the cam shaft 20 by means of a reciprocating rack rod 56 which is formed with a rack engaged with a pinion fixed to the stem of said valve, and whose offset head mounts 15 a roller 58 which engages said cam 70. The drawing shows the reservoir B and primary explosion chamber A as formed in a tubular extension of the cylinder and separated from one another and the working piston C 20 by the discoidal partitions 65 and 43. But this particular construction is non-essential. It is only essential that there be a primary explosion chamber through which the supply of air and the exhaust are effected, and 25 a reservoir interposed between said chamber and the cylinder and through which they communicate.

Fuel from a suitable source (not illustrated) is supplied by a fuel pipe 44, protected by a flame proof 45 and controllable by a hand-valve 49, to a fuel reservoir 46; and is thence led by a branch 48 controllable by a hand valve 50 and protected by a flame proof 60 to the primary explosion chamber A; 30 and to the working cylinder C by a branch 47 controlled by a cam-operated valve 51. Spark plugs P¹ and P of known types, are provided in the primary explosion chamber and cylinder respectively for firing charges 35 therein. The supply of fuel is controlled by the cams 22 and 59 on the cam shaft 20, as follows: The fuel reservoir 46 is divided into a reservoir chamber a and inlet passage b by a diaphragm formed with a valve seat, 40 and a puppet valve 54 spring-seated thereon, which prevents engine-pressures from driving fuel back into the pipe 44 and is lifted at proper times by the cam 59 with which its stem is operably connected. The branches 45 47 and 48 which respectively communicate with the cylinder and primary explosion chamber, open into the reservoir chamber, one below the other, in the order named, at determined distances beneath the normal 50 surface of the fuel charge therein. The valve 51 in the branch 47 is connected with and operated by the cam 22 on the cam shaft 20 by means of an arm 52 on the valve stem and a suitably guided valve-rod 53 55 whose offset head mounts a roller 69 which

rides said cam. The hand-valves 49 and 50 are set as experience and the demand for power dictate.

The above described fuel-control organization may be replaced in engines for other 70 uses by another having substantially the same functions.

My improved engine cycle is as follows: being described as beginning at the end of the exhaust or scavenging stroke as shown in Fig. 2, and when the face of the piston is at the line m—m of Fig. 1. At this instant the air inlet and exhaust valves 27 and 28 are both seated, the tappets 34 and 33 of the valve lever 32 having both been inactively 80 located by the cam 12; the U-passage 42 is free, the valve 55 having been previously opened; the valve 51 is closed and the cylinder C thereby cut off from the fuel reservoir chamber a; but the latter communicates 85 with the fuel supply because the puppet 54 is unseated by the cam 59. During substantially the first quarter of the suction of supply stroke the valves 55 and 54 remain open and the violent suction caused by the 90 piston's advance, (from line m—m to line x—x, Fig. 1) causes the air-inlet valve 27 to be unseated by atmosphere pressure, fresh air to be drawn into the engine and fuel to be drawn into and charge the fuel 95 reservoir chamber a and a certain amount of fuel, depending upon the positions of the valves 49 and 50, to be drawn into the primary explosion chamber A; but none can be drawn into the cylinder C, because the valve 100 51 is closed. The deflector 64 deflects the greater part of the entering air to the passage 66, air-reservoir B and cylinder C and prevents such air from carrying with it sufficient fuel to form an explosive mixture; 105 but a sufficient quantity of fresh air circulates in the primary explosion chamber A to form an explosive mixture therein. Obviously the measure of the suction is the resistance of the spring 29 of the inlet-valve 110 27; or it may be of both the springs 29 and 30; because by properly adjusting their strengths, the exhaust valve 28 may be utilized to admit fresh air during this part of 115 the suction and automatically close as soon as the valve lever fully opens the valve 27.

When the piston has advanced to the line x—x, Fig. 1, the cam 59 permits the puppet 54 to seat and cut off the fuel supply; and during the remainder of the suction stroke 120 no more fuel is drawn into the primary explosive chamber and the cylinder draws in its full volume of fresh air; but without abstracting much, if any, fuel from the chamber A, because the lobe of the cam 12 rides 125 under the pin 15, extrudes the lever 13, rocks the valve lever 32 and causes its tappet 34 to fully open the air inlet valve 27 and by providing free ingress for air, reduce the violence of the suction. At the end of the suc- 130

tion stroke (Fig. 3) the lobe of the cam 12 passes the pin 15 and the spring 16 rocks the lever 13, swings the valve lever 32 to medial position and withdraws its tappet 34 from and permits the air-inlet valve 27 to close; but the other valves are unaffected. During the greater part of the compression stroke all the valves remain closed except valve 55, which remains open until the compression has raised the temperature of the air charge nearly to the ignition point and thereupon, say when the compression stroke is three-quarters or thereabout completed, the primary lobe 71 of the cam 70 functions with raises the rack-rod 56, closes the valve 55 and U-passage 42 and isolates the cylinder C, and during the remainder of the compression stroke the air therein is compressed to the desired degree; but that in the reservoir B and the explosive mixture in the primary ignition chamber A are not further compressed and there is no danger of premature ignition, because there is no explosive in the cylinder and that in the said chamber is separated and not further compressed. At the completion of the compression stroke (Fig. 4) the primary lobe 71 passes and the recess 72 of the cam 70, coacts with and releases the rack-rod 56, which retracts, opens the valve 55 and U-passage 42 and establishes temporary communication between the cylinder C and the reservoir and primary combustion chambers B and A. If the compression in said chambers A and B be nearly sufficient to have caused the temperature of ignition, (say 60 pounds) and the compression (say 120 pounds) in the cylinder considerably higher, putting them in communication will permit air to flow from the cylinder into and compress and raise the temperature of the air and explosive mixture in the reservoir and primary explosion chamber and automatically fire the latter; but to make the cycle positive I provide the spark-plug P¹ of known type thereon. At this instant, also, the cam 22 opens the fuel valve 51 and communication between the fuel reservoir chamber a and the cylinder C. The pressure due to the primary explosion expels the air from the reservoir B into and considerably increases the pressure and temperature in the cylinder and at the same time reacts through the branch 48 upon the charge of fuel in the fuel-reservoir chamber a and (the puppet 54 being closed) forces a determined quantity of fuel through the branch 47 into the cylinder; and instantly thereafter, the second lobe 73 succeeds the recess 72 of the cam 70 in coaction with and extrudes the rack-rod 56, closes the valve 55 and U-passage 42 and isolates the cylinder (Fig. 5) and the cam 22 closes the fuel valve 51.

65 The fuel charged into the cylinder C

either burns or is exploded according to the pressure and temperature therein obtaining and such firing is automatic, if the pressure be reasonably high; but to make the cycle positive I provide the spark-plug P, of a known type. Firing the charge of fuel in the cylinder raises the temperature and pressure therein to the maximum; and because the cylinder is then isolated (the valves 55 and 51 being closed) the maximum pressure does only useful work by advancing the piston 3, and because it is therein confined is not wasted by useless expansion into the air reservoir and primary combustion chamber. As the piston advances the pressure in the cylinder falls and substantially at the instant it has fallen to equality with the pressure of the gases confined in the reservoir and primary explosion chamber, the second lobe 73 of the cam 70 passes the rack-rod 56 and permits it to retract, open the valve 55 and connect and permit said confined gases to expand from the primary explosion chamber and reservoir into the cylinder and do useful work upon the piston, as illustrated in Fig. 6. Toward or at the completion of the power stroke, the recess of the cam 12 runs under the pin 15 and the spring 16 draws the rocking and valve levers 13 and 32 to exhaust position, and the tappet 33 of the latter opens the exhaust valve 28, holds it open during the entire exhaust (Fig. 7); the valve 55 and U-passage remaining open as aforesaid. At the close of the compression stroke the cam 12 closes the exhaust valve, the cam 59 opens the puppet valve 54 and the engine begins another cycle.

It will be observed that the passage 42 discharges into the cylinder C adjacent to and parallel with its end wall 43, there is considerable clearance and the spark-plug P is located some distance from said wall. Therefore the air expelled from the air reservoir will enter the cylinder parallel with said wall and behind the cylinder charge, and extrude and compress it; and in this way I prolong the combustion in the cylinder with said air, enhance efficiency, reduce the initial working pressure and flatten the diagram.

It is evident that engines constructed as above described combine the economy of the Diesel with the simplicity of the Otto or four-cycle system rendered positive and controllable; that the pressure of the charge in the cylinder can be very much higher than that in engines heretofore built, first, because said charge is not an explosive mixture until after the piston passes the dead center, and secondly, because its pressure is augmented by that communicated to it from the primary explosion chamber; that the power possible to develop in Otto-cycle engines as formerly built, with a cylinder and

4

piston of a definite bore and stroke, is increased by the combustion (not explosion) of a quantity of fuel not possible to use in such engines, but practicable to burn in this, with the air driven into the cylinder from the air reservoir B by the primary explosion in the chamber A; that the air expelled from the air reservoir into the cylinder and the products of the explosion (in the primary explosion chamber A) which so expel it, while passing through the narrow and sinuous passage formed by said chambers and the U-passage 42, absorb from their extensive walls heat which is made useful by maintaining the temperature and pressure of such air and gases and ultimately increasing the pre-ignition pressure in the cylinder, in accordance with the law above referred to; and that isolating the cylinder, after it begins its power stroke (by closing the U-passage 42) confines therein the pressure due to the maximum charge and thereby prevents waste of the fuel supplied to the cylinder; which waste occurs in known types of engines designed for this general purpose, but which lack means to isolate the cylinder from its auxiliary chambers, during its power stroke.

If during any cycle, the charge in the primary explosion chamber A were exploded prematurely, the engine would not be harmed; the cycle would not be interrupted, and the only loss would be loss of efficiency, fuel and power. Disastrously premature explosion cannot occur in the cylinder C because no fuel is admitted to it until the substantial completion of the compression stroke, when the cam 22 opens the fuel valve 51. Premature explosion in the primary explosion chamber A would merely cause undue pressure therein and in the air reservoir, because they would be isolated by the closed valves 55 and 51; which at the completion of the compression stroke would be opened; and the cycle would continue uninterrupted.

While the engine illustrated and my improved cycle as described are primarily intended for the use of volatile hydro-carbon fuels, it is evident that the cycle is perfectly adapted to the use of gas or comparatively non-volatile fuels and that the scope of my invention includes engines whose successive operations occur in cycle as above described, howbeit their details are modified to fit them to use particular fuels; as for example such as burn heavy oil and have jets or spray nozzles to spray the fuel into the primary explosion chamber and cylinder to quickly form explosive mixtures with the air therein.

Having thus described my invention, I claim:

1. An improved mode of operating reciprocating internal combustion engines having

a power cylinder and auxiliary chambers connected therewith by a valve-controlled passage by the following sequence of actions, viz;—charging fuel into a primary-explosion chamber; admitting air thereto and to the cylinder; compressing it; exploding the charge in the primary-explosion chamber while it is in communication with the cylinder; admitting additional fuel to the cylinder; isolating the cylinder from the air reservoir, and primary explosion chamber; burning said charge therein; and exhausting the engine.

2. An improved mode of operating reciprocating, internal combustion engines having a power cylinder and auxiliary chambers connected therewith by the following sequence of actions; viz. charging fuel into a primary-explosion chamber; admitting air thereto and to the cylinder; compressing it; exploding the charge in the primary combustion chamber while it is in communication with the cylinder; forcing an additional charge of fuel into the cylinder by the pressure due to said explosion; isolating the cylinder; burning said charge therein; and exhausting the engine.

3. An improved mode of operating reciprocating, internal combustion engines having a power cylinder, and an air reservoir and a primary explosion chamber communicating therewith by a valve-controlled passage, substantially by the following sequence of actions, viz;—charging fuel into the primary explosion chamber; admitting a charge of air through said chamber into the air reservoir and cylinder; compressing said air charge; exploding the charge in the primary combustion chamber while it is still in communication with the air reservoir and cylinder; admitting additional fuel to the cylinder; isolating the cylinder from the air reservoir, and primary explosion chamber; burning said charge therein; and exhausting the engine.

4. An improved mode of operating reciprocating, internal combustion engines having a power cylinder, and an air reservoir and a primary explosion chamber communicating therewith by a valve-controlled passage, substantially by the following sequence of actions, viz:—charging fuel into the primary explosion chamber; admitting a charge of air through said chamber into the air reservoir and cylinder; compressing said air charge; exploding the charge in the primary combustion chamber while it is still in communication with the air reservoir and cylinder; forcing an additional charge of fuel into the cylinder by the pressure due to said explosion; isolating the cylinder; burning said charge therein; and exhausting the engine.

5. An improved mode of operating reciprocating, internal combustion engines hav-

ing a power cylinder, and an air reservoir and a primary explosion chamber communicating therewith by a valve-controlled passage, substantially by the following sequence 5 of actions, viz; charging fuel into the primary explosion chamber; admitting a charge of air through said chamber into the air reservoir and cylinder; compressing said air charge; exploding the charge in the primary 10 combustion chamber while it is still in communication with the air reservoir and cylinder; and thereby forcing air from the reservoir into the cylinder adjacent and substantially parallel with its head; forcing an 15 additional charge of fuel into the cylinder, at some distance from and substantially parallel with its head, by the pressure due to said explosion; isolating the cylinder when the pressure therein substantially 20 equals that in the reservoir and primary explosion chamber; firing the charge in the cylinder in such manner that its combustion will be initiated with the original air charge thereof and sustained and prolonged with 25 the air from the reservoir; and exhausting the engine.

6. An improved mode of operating reciprocating internal combustion engines having a power cylinder and, communicating therewith by a valve controlled passage, an air reservoir and a primary explosion chamber, substantially by the following sequence of 30 actions, viz:—charging fuel into the primary explosion chamber, air reservoir and cylinder; compressing the air in said chambers to a pressure whose temperature is a determined amount less than the temperature of ignition and thereupon isolating the cylinder and completing compression therein; opening communication 35 between the cylinder, air reservoir and primary explosion chamber; firing the charge in the latter, and thereby forcing air from the air reservoir into the cylinder; substantially simultaneously forcing a charge of fuel into the cylinder; isolating the cylinder; allowing the charge therein to expand substantially to equality in pressure with that of the gases confined in the air reservoir and primary explosion chamber and thereupon opening communication 40 among them; and permitting full expansion of the entire products of combustion.

ARTHUR J. HORTON.

der, air reservoir and primary explosion chamber, firing the charge in the latter, and thereby forcing air from the air reservoir into the cylinder; substantially simultaneously forcing a charge of fuel into the cylinder; isolating the cylinder; and, subsequent to the power stroke, exhausting the engine.

7. An improved mode of operating reciprocating internal combustion engines having a power cylinder and, communicating therewith by a valve controlled passage, an air reservoir and a primary explosion chamber, substantially by the following sequence of actions, viz:—charging fuel into the primary explosion chamber; admitting a charge of air into the primary explosion chamber, air reservoir and cylinder; compressing the air in said chambers to a pressure whose temperature is a determined amount less than the temperature of ignition and thereupon isolating the cylinder and completing compression therein; opening communication between the cylinder, air reservoir and primary explosion chamber; firing the charge in the latter, and thereby forcing air from the air reservoir into the cylinder; substantially simultaneously forcing a charge of fuel into the cylinder; isolating the cylinder; allowing the charge therein to expand substantially to equality in pressure with that of the gases confined in the air reservoir and primary explosion chamber and thereupon opening communication among them; and permitting full expansion of the entire products of combustion.
